UNITED STATES PATENT OFFICE.

DANIEL HEPP, OF CHICAGO, ILLINOIS.

BARBED FENCE.

SPECIFICATION forming part of Letters Patent No. 249,522, dated November 15, 1881.

Application filed September 8, 1881. (Model.)

To all whom it may concern:

Be it known that I, DANIEL HEPP, a citizen of the United States, residing at Chicago, in the county of Cook and State of Illinois, have 5 invented certain new and useful Improvements in Barbed Fences; and I do hereby declare that the following is a full, clear, and exact description of the same, reference being had to the annexed drawings, making a part 10 of this specification, and to the letters and figures of reference marked thereon.

Figure 1 of the drawings is a side elevation of my invention. Fig. 2 is a detail view of the barb, and Fig. 3 a view of one of the wire 15 strands bent to form a double loop or eye for the reception of the ends of the barb.

The present invention has relation to that class of barbed fences composed of two wire strands twisted around and upon each other, 20 one of which is bent to form a single eye or loop for connecting thereto a wire barb.

The object of the present invention is to so bend one of the wire strands as to form a double eye or loop, and connecting thereto a wire 25 barb in such manner that a substantial and stronger fence-wire is obtained with increased durability, the barbs being held more securely in position on the strands. These objects I attain by the construction substantially as shown 30 in the drawings and hereinafter described.

In the accompanying drawings, A B represent the two strands composing the fence-wire, which are twisted around and upon each other throughout their entire length. The 35 wire strand A, at intervals, is twisted in the form shown in Fig. 3, so as to form two independent and separate eyes or loops, a b.

The barb C, previous to its being connected to the fence-wire, is in the form of a staple, 40 and after its ends have been passed through the eyes or loops a b they are bent or spread laterally to the plane of the strands, as shown in Fig. 2.

The double loop or eye forms a very secure 45 means of attaching the barb C, and the strand B, which bears between the ends of the barb, assists in holding the same in place.

The difference and distinction between my invention and the strands having the ordinary single loop will be at once apparent. The 50 loops instead of being parallel to the plane of the wire strand are at right angles thereto. The double loop admits the ends of the staple forming the bar passing through the holes, the shanks of the staple being afterward spread 55 laterally to the plane of the wire strand. By the peculiar formation of the double loop, after the barb is inserted and the wire A drawn taut, the barb will present the appearance shown in Fig. 2. The compression produced 60 at the point X will prevent any downward movement of the barb, and the wire strand approaching the base of the eye formed by the compression of the barb will prevent any upward movement of said barb. The construction 65 of the double loop in place of the single loop heretofore in use perfectly clamps and secures the barb in place without the necessity of twisting the wire barb around the strand, or the employment of two separate barbs twisted 70 together after passing them through the eye of the single loop in order to retain them in their relative position, as is common. I therefore desire it to be understood that I lay no claim to a barb fence-wire the main strand of 75 which is twisted to form a single loop or eye for connecting thereto the barb, such construction being admitted as old and in common use.

Having now fully described my invention, what I claim as new, and desire to secure by 80 Letters Patent, is—

In a barbed fence-wire, the strand A, bent at intervals, as shown and described, to form eyes or loops a b, in combination with the strand B and barb C, substantially as and for 85 the purpose set forth.

In testimony that I claim the above I have hereunto subscribed my name in the presence of two witnesses.

DANIEL HEPP.
